UNITED STATES PATENT OFFICE.

ALBERT L. COLE, OF AUBURNDALE, MASSACHUSETTS, ASSIGNOR TO FRANK C. PARMENTER, OF GLOUCESTER, MASSACHUSETTS.

FIRE EXTINGUISHER.

Application filed February 6, 1914, Serial No. 817,042. Renewed January 18, 1922. Serial No. 530,228.

To all whom it may concern:

Be it known that I, ALBERT L. COLE, a citizen of the United States, residing at Auburndale, in the county of Middlesex and State of Massachusetts, have invented a new and useful Improvement in Fire Extinguishers, of which the following is a specification, reference being had therein to the accompanying drawings.

10 This invention relates to fire extinguishers and particularly to portable devices of that character.

The main object of my invention is to provide a fire extinguisher which is compact, efficient and easily handled and manipulated.

A further object is to provide a device which may when necessary be operated with one hand leaving the other hand free.

20 An additional object is to provide a device of such character that it can be employed efficiently in places difficult of access as for instance in between walls and similar places.

25 Other objects of the invention will be more specifically set forth hereinafter.

Briefly, my invention contemplates a fire extinguisher having provision for carrying a supply of fire extinguishing fluid which is forced out through a nozzle in a thin stream or spray by air under compression, the extinguisher being provided with means for compressing the air and with a reservoir for holding compressed air so that the device may be used continuously by operating the compressor or may be operated for an appreciable time by relying upon the storage supply alone.

The preferred embodiment of my invention is illustrated in the accompanying drawings, in which Figure 1 is a side elevation of my fire extinguisher; Fig. 2 is a rear elevation of the same looking from right to left in Fig. 1; Fig. 3 is a plan view; Fig. 4 is a longitudinal vertical sectional view of Fig. 1; Fig. 5 is a sectional plan view looking downwardly with a portion omitted and a part of the plunger not shown; Fig. 6 is a sectional view on line 6—6 in Fig. 5; Fig. 7 is a detail view of the valve showing its position when the extinguisher is in operation; Fig. 8 is a sectional view on line

8—8 in Fig. 7; Fig. 9 is a detail view of the nozzle; and Figure 10 is an enlarged detail sectional view of the valved outlet end of the reservoir.

In the illustrated embodiment of my invention 10 represents a casing, cylindrical in form, having in its forward end an internal thread into which is screwed a cap 11 of conical shape. At the apex of this cap is an internal thread which permits a nozzle 12 to be removably secured thereto. The rear end of the casing is provided with a cap 13. The under portion of the rear end of the casing is made integral with a downwardly extending projection 14 which assumes the shape of the handle of a pistol. Centered within the casing and running nearly the full length thereof is a tube 15 which constitutes the body-portion of a pump or air compressor. 17 is an intake valve for the compressor and 18 represents the outlet valve leading into a storage chamber or reservoir 19 for the compressed air. These valves may be of any suitable construction but I make use of the ordinary ball valve. 20 is a piston of the air compressor 21 is its rod and 22 a handle. The piston rod and handle together I designate as the plunger. The rod 21 is centered in position by the cap or guide box 24. Owing to the peculiar construction of the device it is not necessary to provide a stuffing box or washers for the pump.

The outside diameter of the tube 15 forming the compressor being much smaller than the inside diameter of the casing 10 forming the body-portion of the extinguisher, there is provided a chamber 25 of suitable capacity to contain a quantity of fire extinguishing liquid sufficient to put out an ordinary blaze. The pistol shaped handle 14 is hollow and has an aperture 26 leading into the chamber of the casing.

There is a space between the end of the air compressor and the inner part of the cap 11 which permits a pipe 28 to be inserted into the inner part of the apex of the conical cap 11 and thereby to be brought into abutment with the nozzle 12. This pipe 28 passes under the tube 15 through the aperture 26 down into the hollow handle 14 ending at the valve 30. The purpose of this

pipe is to afford a passage by which the fluid contained in the chamber 25 may be forced out through the nozzle. The valve 30 is one of ordinary construction and is preferably made in the following manner. 31 represents a plug screwed into an internal thread on the end of the pistol shaped handle and the valve 30 is threaded through the plug and provided with a conical end adapted to seat in the end of the pipe 28 to close it. The end of the pipe is held in a central position by a grill 32 which permits liquid to flow downwardly and into the pipe 28 when the valve 30 is lowered as in Fig. 7. In order to permit the chamber 25 to be filled with a fire extinguishing fluid, an opening may be provided at any suitable point as for instance in the handle which may be closed by a pipe plug 33.

20 Referring again to the storage reservoir 19, it will be noticed that it passes out through the casing 10 and then back again into the chamber 25, the latter end opening into the said chamber and being controlled by a valve 35 which prevents the liquid in the chamber from flowing back into the reservoir 19 but does not interfere with the passage of air from the reservoir 19 to the chamber 25. Any form of valve may be used in this connection, that shown being an ordinary ball valve.

The mode of operation of the device is as follows: The valve 30 is closed as shown in Fig. 4 and the plug 33 is removed and the device filled with fire extinguishing liquid, which is poured through the aperture normally closed by the said plug. After the chamber 25 and the space in the handle have been entirely filled with the fire extinguishing fluid the plug 33 is screwed into place tightly and the device is ready for use.

In order that the fire extinguishing fluid may be forced out through the nozzle 12 in a fine spray or stream it is first necessary to operate the compressor and generate an air pressure in the reservoir 19. This is done by moving the piston in the tube 15 by means of the handle 22 in the usual manner of operating an air pump. As the piston is moved from left to right, referring to Fig. 4, the air is drawn in from the atmosphere through the inlet valve 17 and when the piston is moved back again, that is from right to left, the air is compressed closing the inlet valve 17 and opening the outlet valve 18, and allowing the air to pass into the reservoir 19. This operation is continued until the necessary pressure has been generated in the air reservoir 19. When the device is full of fire extinguishing liquid none of the compressed air can leave the reservoir. The device is then ready for use. By opening the valve 30 the compressed air in the reservoir causes the liquid to be forced into the end of the pipe 28 and out through the nozzle 12. The

latter is provided with a transverse slot 37 which operates to spread the liquid into a spray as it passes out of the nozzle. As the liquid flows out through the pipe from the chamber 25, the air under pressure in the reservoir passes through the valve 35 into the chamber and the liquid continues to flow through the nozzle so long as the pressure in the reservoir and in the chamber exceeds the atmospheric pressure. The length of time 75 during which the device will play a continuous stream through the nozzle will depend, of course, upon the amount of compression present in the reservoir and this can be regulated by the length of time the plunger is 80 operated previous to opening the valve 30. When using my device as above described it may be held by the operator with one hand grasping the handle 14 which leaves the other hand free.

Not only is it possible for my extinguisher to be used in the manner already described, that is, by storing the reservoir with compressed air so as to operate it continuously for a few minutes, but it is also possible to 90 use it as an ordinary syringe fire extinguisher. This can be done by grasping the handle 14 of the device in one hand and operating the plunger continuously with the other hand. When so used the device has, however, an advantage over the syringe fire extinguisher because the stream of liquid passing through the nozzle is constant and continuous and not interrupted. For ordinary use where the operator is not hampered for space by the position in which it is necessary to hold the extinguisher, the latter method will generally serve all purposes. Where, however, it is desired to use the device in putting out a fire so located that it may be necessary for the person employing it to use his left hand for some purpose, as for balancing himself in a rocking boat at sea in case the engine of a motor boat should take fire, or in holding himself up to reach a high elevation, or where it is necessary to insert the device in some place where the plunger cannot be operated, as for instance in between the walls of a partition or under a sink or some other place, then the former method can be used, that is, the method of first storing a sufficient pressure and then opening the valve 30.

The great advantage of this method of using the extinguisher is that it may be held in a great many different positions so long as the handle is not held upwardly, and the device will still operate.

Another feature of my invention resides in the means provided for opening up and shutting off the device; that is, the valve 30. This valve is normally closed and so long as it remains closed the device cannot operate. By merely unscrewing this valve the extinguisher is immediately put in op-

eration. This gives the operator using it absolute control so that the spray of fire extinguishing fluid can be quickly turned on or off without any appreciable effort whenever the occasion requires. This feature prevents undue wasting of the extinguishing liquid.

The construction of the nozzle is important because it increases the effectiveness of the device by spreading the stream of fluid so as to cover a comparatively large area, and at the same time does not so reduce the stream into fine spray as to be of no effect.

By arranging the compressor within the casing where it is entirely surrounded by the extinguishing fluid any heat generated by the operation of the compressor is taken up by the fluid and the compressor is kept cool.

It is to be understood that I do not limit myself to the particular construction herein shown, as my invention may be embodied in other structures without departing from the spirit thereof.

What I claim is:—

1. A fire extinguisher comprising a casing having a chamber for fire extinguishing fluid and a nozzle, an air compressor within said chamber, a storage reservoir connected to said air compressor at one end and opening into said chamber at the other end, suitable valves controlling said reservoir, a pipe connecting said chamber with said nozzle and having its lower end open and a valve controlling the lower end of said pipe.

2. A fire extinguisher comprising a casing having a chamber for fire extinguishing fluid and a nozzle, an air compressor centrally located in said chamber and provided with an intake valve and an outlet valve, a storage reservoir for compressed air, one end of which is connected to said outlet valve and the other end of which opens into said chamber, a pipe connecting the said chamber with said nozzle and having its lower end open and a valve controlling the lower end of said pipe.

3. A fire extinguisher comprising a casing having a chamber for fire extinguishing fluid and a nozzle, an air compressor centrally located within said chamber, a storage reservoir having one end connected to said compressor and the other end opening into said chamber, a valve for the compressor end of said reservoir for permitting the compressed air to flow from said compressor into said reservoir, a valve at the other end of said reservoir for preventing the liquid in said chamber from flowing back into said reservoir, a pipe connecting the lowermost portion of said chamber with said nozzle and having its lower end open and a valve controlling the lower end of said pipe.

4. A fire extinguisher comprising a casing having a chamber for fire extinguishing fluid, a nozzle and a depending hollow handle portion, an air compressor connected to said chamber, a pipe connected at one end to said nozzle and extending into the lower portion of said handle and having its lower end open and a valve located in the base of said handle for controlling the end of said pipe.

5. A fire extinguisher comprising a hollow casing having a nozzle and a depending hollow handle, an air compressor for supplying said casing with compressed air, a storage reservoir for storing air under compression, said reservoir being connected at one end to said compressor and at the other end to the interior of said casing, a pipe connected to said nozzle and extending into the lower end of said handle and having its lower end open and means for controlling the flow of liquid through said pipe and said nozzle.

6. A fire extinguisher comprising a hollow casing having a nozzle and a depending hollow handle, an air compressor for supplying said casing with compressed air, a storage reservoir for storing air under compression, said reservoir being connected at one end to said compressor and at the other end to the interior of said casing, a pipe connected to said nozzle and extending into the lower end of said handle and having its lower end open and a valve for controlling the flow of liquid through said pipe and said nozzle.

7. A fire extinguisher comprising a hollow casing having a nozzle and a depending hollow handle, an air compressor centrally located within said casing and provided with an intake valve and an outlet valve, a storage reservoir for compressed air, one end of which is connected to said outlet valve and the other end of which opens into said casing, a pipe connected at one end to said nozzle and extending into the lower end of said hollow handle and having its lower end open and means for controlling the flow of liquid out through said pipe and said nozzle.

8. A fire extinguisher comprising a casing having a chamber for fire extinguishing fluid and provided with a nozzle and a depending hollow handle, an air compressor centrally located within said chamber, a storage reservoir having one end connected to said compressor and the other end opening into said chamber, a valve for the compressor end of said reservoir for permitting said air to flow from said compressor into said reservoir, a valve at the other end of said reservoir for preventing the liquid in said chamber from flowing back into said reservoir, a pipe connected at one end to said nozzle and extending into the lower portion

of said handle and having its lower end open and means for controlling the flow of liquid outwardly through said pipe and said nozzle.

9. A fire extinguisher comprising a casing 5 having a chamber for fire extinguishing fluid and provided with a nozzle and a depending hollow handle, an air compressor centrally located within said chamber, a storage reservoir having one end connected 10 to said compressor and the other end opening into said chamber, a valve for the compressor end of said reservoir for permitting said air to flow from said compressor into said reservoir, a valve at the other end of 15 said reservoir for preventing the liquid in said chamber from flowing back into said reservoir, a pipe connected at one end to said nozzle and extending into the lower portion of said handle and having its lower end open 20 and a valve located in the base of said handle for controlling the flow of liquid outwardly through said pipe and said nozzle.

10. A fire extinguisher comprising a hollow casing having a nozzle at one end and a 25 depending hollow extension constituting a hand grip at the other end, an air compressor within said casing for supplying said casing with compressed air, said compressor having an operating handle in proximity to the hand 30 grip and being operated from that end of the casing opposite the nozzle end, a pipe connected at one end to said nozzle and extending into the lower end of said hollow extension and means at the end of the hollow 35 extension for controlling the flow of liquid outwardly through said pipe and said nozzle.

11. A fire extinguisher comprising a container having a discharge nozzle and controlling means therefor, an air compressor within the container, a reservoir in communication with the inner end of the compressor adjacent to the nozzle end of the container, and a discharge portion at the other 45 end of the container and located within and communicating with the latter, said dis-

charge portion being provided with a valve, substantially as and for the purpose described.

12. A fire extinguisher comprising a container for fire extinguishing liquid having a nozzle and provided with means for controlling the discharge from said nozzle, an air compressor within the container, a reservoir for compressed air, mounted to be 50 supported by the container and connected to receive its supply from said compressor near one end of the container and having a discharge portion near the other end of and communicating with said container, and 55 suitable controlling means intermediate the compressor and reservoir permitting the air to enter the reservoir but preventing its return to the compressing means, and suitable controlling means intermediate of the reservoir and container permitting the compressed air in said reservoir to escape directly to said container to exert its expelling influence on the fire extinguishing liquid 60 upon the opening of the nozzle discharge 65 controlling means.

13. An apparatus for spraying liquids comprising a hollow casing provided with a nozzle at one end and having a depending extension at its other end, a passage in said casing connected to said nozzle, and communicating with the low point of said depending extension, a valve for said passage at that end of the casing remote from the nozzle for controlling the flow of liquid 70 through said nozzle, and means in the main portion of the casing positioned above said depending extension for supplying compressed air to the interior of said casing.

In testimony whereof, I hereunto set my hand in the presence of two subscribing witnesses, this the fourth day of February, 1914.

ALBERT L. COLE.
